UNITED STATES PATENT OFFICE.

MATTHEW VAN WAGENEN, OF SYRACUSE, NEW YORK.

DUMPING-WAGON.

SPECIFICATION forming part of Letters Patent No. 699,262, dated May 6, 1902.

Application filed August 8, 1901. Serial No. 71,327. (No model.)

To all whom it may concern:

Be it known that I, MATTHEW VAN WAGENEN, of Syracuse, in the county of Onondaga, in the State of New York, have invented new 5 and useful Improvements in Dump-Wagons, of which the following, taken in connection with the accompanying drawings, is a full, clear, and exact description.

This invention relates to improvements in 10 dump-wagons, having more particular reference to that class in which the bottom wall of the receiving-chamber consists of movable sections hinged to the lateral side walls of the box and having their adjacent free ends adapted to meet substantially midway between said 15 side walls, said movable bottom sections being elevated by a suitable drum and cable and adapted to open or drop by gravity when released.

20 The object of my invention is to provide certain improvements in this class of dump-wagons—viz., first, compensating mechanism for taking up the sag or inequality of movement of the movable bottom-wall sections; 25 second, means for preventing the accumulation of dirt or other obstacles in the joints between the hinged bottom sections and side walls of the box; third, mechanism for preventing the accidental movement of the bottom sections of the dump-box to their dumping position while carrying the load; fourth, means for holding the operating-pawl and stop-dog for the reel or drum in their inoperative positions when the drum is released 35 in the act of dumping the wagon; fifth, connections between the body of the wagon and front axle for permitting the lateral rocking movement of the body of the wagon upon the fifth-wheel without liability of unduly straining the king-bolt or overturning the wagon-box when the front axle is turned lengthwise 40 of the box or at right angles with the rear axle.

To this end the invention consists in the combination, construction, and arrangement 45 of the parts of a dump-wagon, as hereinafter fully described, and pointed out in the claims.

Referring to the drawings, Figure 1 is a longitudinal vertical section of the upper portion of a dump-wagon embodying my various improvements. Fig. 2 is a sectional view taken 50 on line 2-2, Fig. 1. Fig. 3 is an enlarged top plan view of a portion of one side of the su-

perstructure or dump-box, showing particularly a portion of the drum and its bearing, the ratchet secured to the drum, the operating member for rotating the drum, the stop pawl or lever for preventing the return movement of the drum, and the mechanisms for controlling the movement of the stop-lever. Fig. 4 is a detail view of the portion of the stop-lever, showing the spring-catch and locking-dog. Fig. 5 is a detail view of the upper end of the king-bolt, showing the elongated opening for receiving the same. Fig. 6 is a detail view of the fifth-wheel-bearing-sections. Fig. 7 is a rear view of a portion of the dump-box, showing the compensating lever and also showing the open joint between one of the side walls and the adjacent hinged bottom section. Fig. 8 is a view similar to Fig. 7, showing a slightly-modified compensating mechanism.

Similar reference characters indicate corresponding parts in all the views.

In the drawings I have shown a portion of 75 a dump-wagon consisting of a superstructure or box 1, a front axle 2, a fifth-wheel 3 between the front end of the dump-box and front axle, a king-bolt 4, and a rotary drum 5.

The dump-box 1 preferably consists of side, 80 front, and rear walls 6, 7, and 8 and movable bottom sections 9, having upturned sides 10, which are hinged to their upper edges at 11 to the side walls 6. These movable bottom sections are normally arranged in a substantially 85 horizontal position and meet in a plane substantially midway between the side walls 10 when in their closed position, said side walls 10 being substantially coincident with and forming a continuation of the side walls 6 and 90 are formed with inner beveled edges 12, adjacent to the lower edges of the side walls 6 for preventing the accumulation of dirt or other obstacles which are liable to interfere with the perfect operation of the movable bottom sections. The meeting edges of the bottom sections are also preferably beveled at 13 for a similar purpose—that is, to prevent the accumulation of any dirt or stones which might prevent the closing of the sections. I 95 preferably provide the meeting edges of each of the sections with rollers 14, which are mounted in suitable brackets 15 and are adapted to receive chains or cables 16.

The drum 5 is provided with eyes or equivalent fastening means 17, to which are secured the front ends of the cables 16, and in order to properly guide the cables and facilitate the elevation of the bottom sections I provide the front wall 7 of the box with suitable idlers 18, which are separated a distance substantially equal to the distance between the idlers 14 at opposite sides of the meeting edges of the bottom wall. The rear ends of the cables 16 are passed under the idlers 14 and are connected to a suitable compensating lever or equivalent device 19. This compensating device is pivoted to the rear wall 8 at 20, its opposite ends being hook-shaped and adapted to receive the links of the chain or other loop if the cable is employed, and it is evident from the foregoing description and the accompanying drawings that when the chains are wound upon the drum 5 in the act of raising the bottom sections to their closed position the inequality in the movement of the hinged sections is readily taken up by the compensating lever 19. Although this compensating mechanism just described is particularly simple and efficient, it is evident that other means may be employed with equal efficiency, and at Fig. 8 I have shown a continuous chain 16' and an idler 19', pivoted at 20' to the rear wall 8, the intermediate portion of the chain being passed over the idler 19', and the opposite ends of said chain are secured to the eyes or similar fastening means 17 on the drum, it being understood that should one of the bottom sections close before the other the continued rotation of the drum 5 would readily draw the other section into its closed position.

In the preferred form of compensating mechanism seen in Fig. 7 I have shown a supporting-bracket 21, arranged in the form of a loop, open at its upper end and having its lower end united to the lower wall beneath the pivotal pin 20, so that if from any cause the pivotal pin should break or get out of place the lever 19 would still be retained in substantially its normal position, and thereby prevent the accidental dumping of the wagon.

The drum 5 is provided with a ratchet-wheel 22, which may be secured to the drum in any desired manner not necessary to herein illustrate. The ends of the drum are journaled in suitable boxes or bearings 23, fastened to the inner face of the side walls 6, and said bearings are preferably open at their upper ends for permitting the removal of the drum whenever desired without removing the bearings. Loosely mounted on the drum 5, in proximity to and preferably at the outer side of the ratchet-wheel 22, is an operating member 24, arranged in the form of a hand-lever, and pivotally mounted upon the operating member is a pawl 25, having its forward end pivoted at 26 and its rear end adapted to engage the teeth of the ratchet-wheel 22 in such manner that as the lever is elevated the drum

will be rotated in the bearing 23, the pawl 25 being free to ride over the teeth as the hand-lever is lowered. Pivotally mounted upon the adjacent side wall 6 is a stop-lever 27, which is preferably pivoted at its intermediate portion at 28 to a suitable bracket or stop 29, secured to the side wall 6, the rear end of said stop-lever being adapted to engage the teeth of the ratchet-wheel in advance of and directly beneath the pawl 25, said lever 27 being provided with a rearward extension 30, which is connected by a spring 31 to a suitable eye or equivalent fastening member 32, secured to the front wall 7 of the box 1, the spring 31 serving to hold the ratchet-engaging end or shoulder of the lever 27 in engagement with ratchet-teeth and at the same time permitting the teeth to readily pass under said shoulder. The forward end of the lever 27 extends a suitable distance beyond the pivot 28 and preferably in front of a seat 33 and is provided with a foot-engaging portion 34 and a locking-dog 35. This locking-dog is pivoted to the lever 27 at 36, its upper end being provided with a foot or hand engaging portion 37, and its lower end extends downwardly and is adapted to engage a suitable wearing-plate or stop-face 38, secured to a platform 39, beneath and in front of the seat-support. This locking member 35 serves to hold the rear end of the lever 27 in engagement with the ratchet-teeth when the bottom sections 9 are in their position for retaining a load and serves to prevent any accidental dumping of the wagon during the transportation of the load from one place to another. This is a particularly simple and efficient means for carrying out this object of my invention, and it is believed to be broadly new in this class of dump-wagons. The rear end of the lever 27 is so arranged relative to the pawl 25 that when the forward end of the lever is depressed the rear end of said lever is elevated out of the path of the teeth of the ratchet-wheel and simultaneously engages and elevates the pawl 25 out of the path of said teeth. This operation is for the purpose of releasing the ratchet and permitting the drum to rotate freely in the act of dumping the load from the movable bottom sections. In wagons of this class it has been the custom to rely upon the operator for holding the pawls and stop-dog out of engagement with the ratchet-wheel during the operation of dumping the load, and inasmuch as the ratchet-wheel rotates with considerable speed and the strain thereon being considerable it frequently happens that one or the other of the pawls will engage or slightly engage one or more of the teeth during the unwinding of the drum and either break the teeth or pawls, and in order to obviate this liability I provide the front end of the vehicle with a suitable spring-catch 40, having a shoulder 41, adapted to engage the upper face of the forward end of the lever 27 when the pawl 25 and lever 27 are disengaged from the ratchet-

wheel, thus preventing any liability of the pawls 25 and 27 engaging with the teeth of the ratchet when the drum is being unwound.

The platform 39 is provided with a suitable 5 aperture 42 and a wearing-plate 43, also formed with an aperture aligned with the aperture 42 for receiving the upper end of the king-bolt 4. These apertures are preferably elongated laterally, and the lower end of the 10 king-bolt is firmly secured by a tapering fit in the axle 2 of the wagon. It is therefore evident that as one of the front wheels passes over the obstruction or the axle 2 tilted from any cause the king-bolt is free to ride in the 15 apertures of the platform 39 and plate 43.

The lower section of the fifth-wheel (represented in Fig. 6) is provided with raised 20 portions 50, having a substantially flat upper face and inclined ends, which permits the 25 axle or vehicle-body to rock one upon the other a limited distance.

In the operation of my invention after the drum 5 has been rotated in the usual manner for drawing the bottom sections to their 25 closed position the locking member 35 is moved to its position (seen in Fig. 1) for holding the lever 27 in engagement with the ratchet-teeth during the filling and transportation of the load. When desired to dump the 30 load, the lever 35 is rocked on its axis toward a horizontal position, whereupon the lever 27, or, rather, its forward end, is depressed until engaged by the catch 40. This operation 35 forces the pawl 25 and adjacent end of the lever 27 out of engagement with the teeth of the ratchet-wheel, whereupon the bottom sections automatically drop to discharge the load, the drum 5 and ratchet-wheel 22 being free to revolve for unwinding the chain of 40 the cable. When drawing the bottom-sections together to their closed position by the operating-lever 24, should one of the doors close before the other the chain closing said door would become tight as the drum continued to rotate, and would thereby rock the 45 compensating lever 19 upon its pivot 20, thereby tensioning the loose side of chain and drawing the other section firmly into place.

The operation of my invention will now be 50 readily understood upon reference to the foregoing description and the accompanying drawings, and it will be noted that some change may be made in the detail construction and arrangement of the various features 55 of my invention without departing from the spirit thereof. Therefore I do not limit myself to the precise construction and arrangement shown and described.

Having thus described my invention, what 60 I claim, and desire to secure by Letters Patent, is—

1. In a dump-wagon the combination with 65 hinged bottom sections of a dump-box, a rotary drum and cable connected to elevate said sections to their closed position, means for rotating the drum, a yielding stop for holding the drum in its adjusted position and a lock-

ing member pivotally mounted on the stock and arranged to engage a fixed member on the wagon for holding said stop from yielding. 70

2. The combination with the hinged bottom sections of a dump-box adapted to drop by gravity, a rotary drum connected to close said sections, means for rotating the drum, a stop pawl or lever for holding the drum in 75 its adjusted position, said stop-pawl being movable for simultaneously releasing the drum and disconnecting its rotating means therefrom, for the purpose described.

3. The combination with a dump-wagon 80 having movable bottom sections, a drum, a cable connected to the drum and to said movable sections, a ratchet-wheel secured to the drum, an operating member or lever loosely mounted on the drum and provided with a 85 pawl adapted to engage the teeth of the ratchet for rotating the same in one direction, a stop-pawl for engaging the ratchet-teeth and operable manually to release the former pawl from engagement with the 90 ratchet, and means for locking the stop-pawl in engagement with said teeth for preventing the unwinding of the drum.

4. The combination with a dump-wagon 95 having movable bottom sections hinged to its side walls, a rotary drum at one end of the movable sections, a rocking member at the other end, cables or chains connected to said drums and to said rocking member at opposite sides of its pivot, the intermediate 100 portion of said cable being connected to the bottom sections and means for rotating the drum.

5. In a dump-wagon, the combination with 105 a box having hinged bottom sections, a rocking member pivoted to the rear wall of the box above the bottom sections, a drum secured to the box at the other end of the bottom sections, a cable or cables having their opposite ends connected to the rocking member 110 and to said drum and their intermediate portions connected to the movable sections, means for rotating the drum to wind the cable thereon, additional means for preventing the return movement of the drum and a locking member for holding the latter means in its operative position. 115

6. In a dump-wagon, a dump-box having its bottom wall formed of sections having upright side portions hinged to the side walls of the box, the upper edges of said upright portions of the sections being beveled for preventing the accumulation of dirt or other substance thereon and discharging the dirt therefrom onto the horizontal portions of the 125 sections.

7. A dump-wagon having hinged bottom walls, a rotary drum having cable connected thereto and to the bottom walls for the purpose described and a rocking member mounted on the frame of the wagon and connected to said cable at opposite sides of its axis for the purpose set forth. 130

8. In a dump-wagon the combination of a

front axle and frame, the axle having an opening and the frame having a platform provided with an elongated opening, a king-bolt inserted through the elongated opening in the platform and having its lower end fitting closely in the opening in the axle and a fifth-wheel comprising upper and lower sections surrounding the king-bolt the lower section of the front and rear raised surfaces inclining downwardly at their opposite ends for the purpose set forth.

9. In a dump-wagon, the combination with a dump-box having movable bottom sections hinged to its side walls, a compensating member secured to the box at the rear ends of the bottom walls, a drum revolvably mounted on the box at the front end of the bottom section, a cable or chain connected to the compensating member and drum and also to the bottom sections, a ratchet-wheel secured to the drum, an operating member having a pawl movable into and out of engagement

with the teeth of the ratchet for rotating the drum and releasing the same, a stop-lever pivotally supported at its intermediate portion ²⁵ and having its rear end adapted to engage the teeth of the ratchet beneath the pawl, a spring for yieldingly holding the stop-lever in engagement with the ratchet-teeth, a locking member for positively locking said lever in ³⁰ engagement with the ratchet-teeth, said locking member being movable for releasing the lever and the lever being arranged to move out of engagement with the teeth and to simultaneously force the pawl out of the path ³⁵ of said teeth, and means for holding the lever in its inoperative position.

In witness whereof I have hereunto set my hand this 2d day of August, 1901.

MATTHEW VAN WAGENEN.
